UNITED STATES PATENT OFFICE

173,000

PLATFORM FOR AN ANIMATED FIGURE

Raymond H. Turner, St. Louis, Mo.

Application August 31, 1953, Serial No. 26,641

Term of patent 14 years

(Cl. D34—15)

To all whom it may concern:

Be it known that I, Raymond H. Turner, have invented a new, original, and ornamental Design for a Platform for an Animated Figure, of which the following is a specification, reference being had to the accompanying drawing, forming a part hereof.

Fig. 1 is a top plan view of a platform for an animated figure, showing my new design;

Fig. 2 is a side elevational view thereof;

Fig. 3 is an end elevational view thereof, looking at the right end in Figs. 1 and 2;

Fig. 4 is an end elevational view looking at the left end in Figs. 1 and 2; and

Fig. 5 is a perspective view thereof.

I claim:

The ornamental design for a platform for an animated figure, as shown.
